UNITED STATES PATENT OFFICE.

HARRY B. WHITE, OF CANTON, OHIO, ASSIGNOR TO THE HOOVER COMPANY, A CORPORATION OF OHIO.

SUCTION CLEANER.

Application filed December 21, 1925. Serial No. 76,660.

The purpose of the invention is the provision of an improved handle control mechanism for application to a suction sweeper, and a particular object is the provision of 5 such improved handle control mechanism.

An essential object of the invention is in the construction of a handle control mechanism having provision for automatically securing the handle in an upright or stor- 10 age position.

A further object is in the construction providing means limiting the handle movement to a definite predetermined amount under normal sweeper operating conditions.

15 Other objects of the invention reside in the provision of simple foot actuated or automatically operating means for securing the handle in upright position, for limiting the handle movement to a predetermined arc or for allowing full free swing 20 of the handle, either, as required for the particular sweeper condition.

Other objects of the invention such as 25 simplicity of construction, ease of manufacture, rugged construction and such like advantages and improvements disclosed in the invention will be apparent on reading the specification considered in connection with drawings in which:

30 Figure 1 is a side elevation of the handle control in normal operating position;

Fig. 2 is an end elevation of the structure shown in Fig. 1;

Fig. 3 is a side elevation of the foot 35 lever;

Fig. 4 is an end elevation of Fig. 3;

Figs. 5 and 6 are respectively side and top plan views of the pawl member; and

Fig. 7 is a diagrammatic showing simi- 40 lar to Fig. 1 with the handle in its lowermost position.

A broken section of a suction sweeper casing is indicated at 10 appropriately secured to which is a pin 11, on which is 45 pivotally mounted handle bail 12 carrying an appropriate sweeper operating handle, not shown.

Formed integral with or appropriately secured to the lower end of bail member 12 50 is a segment 13 providing at its outer edge a wide or normal working stroke limit, notch 14 having end limit shoulders 15 and 16, cam lug 17 and storage notch 18.

Also mounted on pin 11 there is provided 55 foot lever 19 having an upstanding latch

lug 20 carrying pawl latch pin 21. The outer end of foot lever 19 is provided with foot operation pin 22 for appropriate operation of foot lever 19. Foot lever 19 is further provided on its top edge with a 60 spring retaining lug 23 and on its bottom edge with limit lug 24 to prevent the foot lever rising above its proper position.

On casing 10 there is a pawl mounting pin 25 on which is pivotally mounted pawl member 26. Near the top of pawl member 25 and on the inside edge there is provided a pawl latch pin recess 27, and on the outer edge there is provided a double bent lug comprising a channel shaped guide in which 65 the side guide portions are indicated as 28 and 29, and the base latch portion is indicated at 30, guide portions 28 and 29 co-operating with segment 13 to insure registry of latch portion 30 with latch notches 70 14 and 18. At the bottom extending from the inner edge of pawl 26 is a spring retaining means 31 which is hook-shaped and turned upwardly.

Spring member 32 is adapted to seat on 75 pin 11 and has two outwardly extending arms 33 and 34 adapted to be compressed one toward the other and secured, the one 34 under lug 23 on foot lever 19, and the other 33 on the pawl spring retainer 31. 80

The operation of the handle control is that in handle storage position the parts are positioned as in Fig. 1 excepting that the handle and segment are pivotally displaced counterclockwise sufficiently to allow latch 85 30 to be positioned in storage notch 18. To bring the handle into normal operative position it is necessary to depress foot lever 19 by application of pressure on operating pin 22, depressing pawl latch pin 21 forcing 90 back pawl 26 as the pin rides over the inner rounded top edge thereof until the pin enters latch pin recess 27 at which time the pawl returns to approximately its original position under the urge of spring arm 33 and thus pin 21 is latched in recess 27. Now, pressure applied to the handle will cause cam lug 17 to ride over latch base 30 and the handle may be lowered. As lug 17 rides over latch 30 the pawl 26 is forced backward 95 sufficiently to release pin 21 from recess 27 and the foot lever 19 and pawl 26 are restored to original position excepting that latch 30 rides on the face of segment 13 instead of being seated in one of the notches. 100 105 110

As soon as the handle is lowered sufficiently to allow latch 30 to fall into the limiting notch 14 the foot lever 19 and pawl 26 are completely restored to position as shown in Fig. 1. On operation of the cleaner with the handle control so positioned all parts maintain their positions excepting the segment which may oscillate through the arc determined by the limits imposed upon latch 30 by stop shoulders 15 and 16 of working notch 14.

By again depressing foot lever pin 22 the foot lever and pawl will again take the positions shown in Fig. 7 and the handle may be lowered to its lowermost limit or to any position intermediate that defined by limit shoulder 15 and the lowermost position.

From the last described condition of operation either of two steps may be taken. To accomplish either, the handle is raised to a nearly vertical position or until cam lug 17 acts to release latch pin 21 from latch pin recess 27, which release is indicated by an audible snap from which condition further raising of the handle will allow latch 30 to drop into notch 18 for a storage position or a lowering of the handle from the snap position will allow latch 30 to enter limiting notch 14.

From the foregoing description it will be seen that there is provided a convenient handle control means rugged in construction and easy to operate.

Having thus described the invention as regards both its construction and operation with that degree of particularity and definiteness required by statute, I claim:—

1. A handle control mechanism comprising a relatively stationary member, a pivot mounted thereon and a handle member mounted on the pivot, a segment, having notches therein, mounted on the handle member, a pawl member pivotally mounted on the stationary member and having a latch portion, the latch portion biased to enter the

notches in the segment, a pawl latch pin and means selectively causing engagement or disengagement of the pawl and pawl latch pin and pawl with each other and allowing or preventing entry of the pawl latch into the notches in the segment.

2. In combination in a handle control mechanism, a relatively stationary member, a handle pivotally mounted thereon, a segmental member carried by the handle, the segmental member having notched portions formed therein, a pawl member having a latch portion formed thereon, a pivoted operating means having a pawl latch pin thereon whereby actuation of the pivoted operating means interposes the pawl latch pin in the path of the pawl preventing active coaction of the pawl latch and the notched portions of the segment.

3. A handle control mechanism comprising a relatively stationary member, a handle member pivotally mounted on the stationary member, a segmental member mounted on the handle member, the segmental member having a substantially arcuate edge portion, notch-like recesses in the edge portion of the segment and a cam surface formed on the edge portion of the segment, a pawl pivotally mounted on the stationary member and biased toward the edge portion of the segment, the pawl member having a latch portion acting normally under influence of the pawl bias to enter the notch-like recesses of the segmental member, means actuatable to counteract the pawl bias and to withdraw the pawl latch portion from normal coaction with the notch-like recesses, said means holding the pawl in its withdrawn position and other means comprising the aforementioned cam surface to release the pawl latch holding means.

Signed at North Canton in the county of Stark, and State of Ohio, this 15 day of December, A. D. 1925.

HARRY B. WHITE.
